CAN FILLING MACHINE

Walter J. Dobbins 3rd, Little Falls, N. J., assignor
to American Can Company, New York, N. Y., a
corporation of New Jersey

Application March 13, 1950, Serial No. 149,317

2 Claims. (Cl. 226—19)

1

The present invention relates to machines for canning meat products and the like in which the product is forced into containers or cans by a presser, plunger or piston and has particular reference to devices for wetting the product contacting surface of the plunger with a film of steam, water, or other suitable fluid to protect this surface against the adherence of the product thereto. This is an improvement upon the Can Filling Machine disclosed in United States Patent No. 2,336,415, issued December 7, 1943, to R. E. J. Nordquist et al.

In the packing of meat products into cans it is important that the product fill the can solidly so that all air is excluded from the can to protect the product against spoilage. It is also important that the top of the product in the can be left smooth and even at a predetermined level below the top of the can to allow for proper vacuumizing and application of the cover to the can. Any of the product that extends above this level, especially adjacent the edges of the can is liable to get caught in the seam which unites the cover to the can and thus cause a defective seam which may result in subsequent spoilage of the product.

In machines of the type that utilizes plungers to pack and press the meat product tightly into cans, the product frequently clings to the product contacting face of the plunger when the plunger is withdrawn from the can, after the packing operation, and thus the adhering product is lifted sufficiently to disrupt the solid condition of the pack and sometimes sufficiently to cause adherence to the can flange causing improper closing of the can.

The instant invention contemplates overcoming these difficulties by the provision of devices for wetting or otherwise conditioning with water, steam, or other suitable fluids the contacting face of the plunger to protect it against adherence of the product thereto.

An object of the invention is the provision in such a product packing or filling machine of devices which operate to project a spray of atomized steam, water, or other suitable conditioning fluids against the product contacting faces of the pressure plungers to wet or moisten and thereby protect these faces against adherence of the product thereto during the product pressing or packing operation.

Another object is the provision of such devices which may be moved into and out of operating position for readily cleaning the spray head of the devices.

Numerous other objects and advantages of the invention will be apparent as it is better understood from the following description, which, taken in connection with the accompanying drawings, discloses a preferred embodiment thereof.

Referring to the drawings:

2

Figure 1 is a top plan sectional view of a can filling machine embodying the instant invention, with parts broken away; and

Fig. 2 is an enlarged sectional view taken substantially along the line 2—2 in Fig. 1, with parts broken away and parts shown in dot and dash lines.

As a preferred or exemplary embodiment of the instant invention the drawings illustrate 10 principal parts of the meat product packing machine disclosed in the above mentioned Nordquist Patent 2,336,415. In such a machine the meat product is fed into a filling and measuring sleeve which upon being filled, is inserted into an 15 empty can. A plunger located within the sleeve presses or compacts the product into a solid mass in the can as the sleeve is withdrawn from the can. After full withdrawal of the sleeve, the plunger is withdrawn, thus leaving the product 20 in the can. It is upon this withdrawal of the plunger that the sticky product clings to the plunger and it is to the overcoming of this difficulty that the instant invention is directed, the remedy lying in the effective wetting or otherwise conditioning of the product contacting face 25 of the plunger prior to the product pressing or compacting operation.

Empty cans A to be filled, moving in a substantially continuous procession in timed and spaced order, are fed into the machine by a continuously rotating star wheel 10 and are received on vertically movable lifter pads as shown in the Nordquist patent. As the cans enter the machine they pass under a stationary table 12 formed with a conduit 13 through which the meat product, indicated by the letter B, is fed into the machine under pressure. The conduit terminates in an opening 14 formed in the top of the table 12.

The table 12 supports a rotatable disc 16 which is mounted on a continuously rotating shaft 17 as shown in the Nordquist patent. This disc slides across the table during its rotation and thus covers the meat product outlet 14. The disc carries a plurality of filling and measuring sleeves 18, vertically and slideably disposed in bearings 19 formed in the disc 16. Each sleeve encloses a measuring chamber 21 in the lower end of which is located a vertically movable pressure plunger or piston 22 as shown in the Nordquist patent. These sleeves 18 and plungers 22 are disposed above and in vertical alignment with the lifter pads and the cans carried thereon, and are moved with the disc member 16 into register with the meat outlet 14 in the table 12 to receive a measured charge of the meat for insertion into a can on its lifter pad.

In accordance with the Nordquist patent a sleeve 18 and its plunger 22 as they approach the table 12 to receive a charge of the meat product, are in their lowered position, flush with the bottom of the disc member 16 as best shown in

Fig. 2. It is while the sleeve and its plunger are in this position that the bottom or contacting face of the plunger is moistened to prevent adherence of the meat product to the plunger face as hereinbefore mentioned. This moistening or wetting of the plunger face is brought about preferably by spraying, for example, atomized water against the bottom of the plunger. For this purpose a conventional atomizer nozzle 25 is located under the disc members 16 adjacent the edge of the table 12 as shown in the drawings.

The nozzle 25 is carried on the inner end of a horizontal arm 26 which at its outer end is formed with a vertical hub 27 having trunnions 28 which are mounted in bearing lugs 29 formed on a bracket 31 secured to a column 32 which constitutes a part of the frame of the Nordquist machine. With this manner of mounting the arm 26, the nozzle 25 may be readily swung out into the open, as shown in dotted lines in Fig. 1, for cleaning or adjusting.

The nozzle 25 is connected by a water supply tube 34 to a water channel 35 formed in the upper portion of the hub 27. The tube is carried on the arm 26. The upper end of the water channel 35 communicates with a supply pipe 36 which leads from a reservoir 37 containing a supply of water. The reservoir is mounted on the side of the column 32.

The nozzle 25 is also connected by an air tube 41 to an air channel 42 formed in the lower portion of the hub 27. This air tube is disposed adjacent the water tube 34 on the arm 26. The lower end of the air channel 42 communicates with a supply pipe 43 which leads from any suitable source of compressed air. The water and the air from their respective tubes 34, 41 are mixed in the nozzle 25 and are discharged therefrom in a fine spray which is continuously projected against the bottom of the rotating disc member 16 as best shown in Fig. 2.

Hence as the rotating disc member 16 carries a measuring sleeve 18 and its plunger 22 into position over the nozzle 25 the bottom face of the plunger receives a film or coating of the water spray and is thereby wetted or moistened for the packing operation.

As fully explained in the Nordquist patent, the advancing sleeve 18 and plunger 22 move into a position over the meat outlet 14 and as they pass this outlet the plunger 22 moves up into the sleeve and permits the meat product under pressure to rise up into the measuring chamber 21 in the sleeve. When a measured charge of the product has been received in the chamber the plunger ceases its upward travel and the rotating disc member cuts off communication with the meat outlet by advancing the sleeve 18 out of register with the outlet.

As the disc 16 continues to rotate, it carries the filled sleeve 18 beyond the table 12. The lifter pad then raises the can into position under the sleeve and while in this position the sleeve and the plunger move down in unison into the can. The plunger continues to move down slowly in the can and thus compresses the meat into a solid mass while the sleeve is withdrawn. When the sleeve is fully withdrawn, the plunger is lifted away from the product in the can and the filled can is discharged from the machine. This completes the cycle of operation of the machine as disclosed in the Nordquist patent.

However it is at the point in the can filling operation where the plunger is lifted away from

the product in the can, that the water coated face of the plunger manifests itself. The water coating on the face of the plunger 22 protects the face against the adherence of the product thereto. Thus the plunger face rises freely from the product and leaves the top surface of the product smooth and even. There is thus nothing clinging to the face of the plunger to effect an unsanitary condition in the machine and likewise the product in the can is properly placed so that a cover may be readily applied thereto in the usual manner.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. In a machine for packing meat or other sticky products into containers, the combination comprising a conveyor member, a packing plunger having a product contacting face, said plunger being mounted for reciprocation in said conveyor and movable by said conveyor in a predetermined path, an oscillatable atomizer member having a hub adjacent one end and an atomized nozzle adjacent the opposite end thereof, fixed spaced bearing lugs mounted adjacent the path of said conveyor, said hub having trunnions at opposite ends thereof journaled in said bearing lugs, a liquid supply channel in said atomizer member leading from one of said trunnions to said nozzle, an air channel in said member leading from the other of said trunnions to said nozzle, and conduits leading from said trunnions to sources of liquid and compressed air, respectively, to supply liquid and air to said nozzle for atomizing and projecting said liquid into the path and against said face of the plunger when the nozzle is in operative position, said atomizer member being oscillatable on said lugs to inoperative accessible position for cleaning and adjusting said nozzle.

2. In a machine for packing meat or other sticky products into containers, the combination comprising a conveyor member, a packing plunger having a product contacting face, said plunger being mounted for reciprocation in said conveyor and movable by said conveyor in a predetermined path, a fixed bearing adjacent the path of said plunger, an arm pivotally mounted at one end on said bearing, a fluid projecting nozzle mounted on the free end of said arm and normally directed in an operative position toward the path of said product contacting face of the plunger for projecting a film of fluid onto said plunger face to prevent adherence of the product thereto during a subsequent packing operation of the plunger, said arm and nozzle being oscillatable on said bearing away from said path of the plunger to an inoperative and accessible position for cleaning and adjusting said nozzle.

WALTER J. DOBBINS 3RD.
